UNITED STATES PATENT OFFICE.

JOSEPH B. MORRILL, OF ST. LOUIS, MISSOURI, ASSIGNOR TO WESTERN ELECTRIC COMPANY, INCORPORATED, OF NEW YORK, N. Y., A CORPORATION OF NEW YORK.

REPEATER CIRCUITS.

Application filed November 6, 1920. Serial No. 422,199.

To all whom it may concern:

Be it known that I, JOSEPH B. MORRILL, a citizen of the United States, residing at St. Louis, in the county of St. Louis and 5 State of Missouri, have invented certain new and useful Improvements in Repeater Circuits, of which the following is a full, clear, concise, and exact description.

This invention relates to electric circuits, 10 especially repeating systems, and an object of the invention is to reduce distortion of waves transmitted by such systems.

As is well known in the art, weak currents or signals may be amplified to any desired degree by impressing them on one or 15 more vacuum tube amplifiers arranged to work into each other by suitable circuit connections. In employing the vacuum tube as an amplifier, it has been found that the tube 20 works most efficiently when the impedance between the control electrode and the cathode is composed substantially of resistance with no capacity component. In that form 25 of a vacuum tube wherein the control electrode or grid is within the tube and adjacent to the cathode, there is present a certain amount of capacity between the cathode and the grid, dependent in value upon the size of the electrodes and the distance there- 30 between. This capacity effect is generally negligibly small for currents of low frequency, but if the frequencies impressed on 35 the tube are relatively high the capacity effect may be quite appreciable and cause a certain amount of distortion in the current waves to be repeated.

In accordance with this invention, the undesired grid-cathode capacity may be substantially neutralized by including in a 40 shunt path to the grid and cathode, a high resistance and an inductance, the inductance having such a value as to tune with the grid capacity for the frequency or band of frequencies which are of the most importance 45 in the impressed currents. The high resistance element preferably employed in connection with the inductance element serves to broaden the tuning of the circuit including the grid capacity and the inductance element whereby uniform transmission is secured over a wider range of frequencies. 50

This invention will be better understood by reference to the following detailed de-

scription taken in connection with the accompanying drawing which represents a 55 preferred embodiment of this invention.

Referring to the drawing, 5 is a vacuum tube amplifier having a cathode 6, a control or grid electrode 7, and an anode 8. Heating current for cathode 6 is supplied by a 60 battery 9, space current for the tube is supplied from a source of voltage 10. The input electrodes 6 and 7 of the tube, are connected to an incoming line 11, 11 by means of a transformer 12. The output electrodes 65 8 and 6 of the tube, are connected to the outgoing line 13, 13, by means of the transformer 14. With such an arrangement, tube 5 is adapted to impress upon outgoing line 13, 13, amplified current received from incoming line 11, 11.

It has been found even where the frequency of the incoming current is as low as 1,000 cycles, that the impedance between grid 7 and cathode 6 consists not only of 75 a resistance component but has an appreciable capacity component. This capacity component produces distortion in the repeated signals and is, therefore, undesirable 80 particularly for ultra-audio frequencies 80 where the effect is most marked. In accordance with this invention, this undesired grid capacity is substantially neutralized or effectively eliminated by inserting, in a path 85 in shunt to the grid and cathode, an inductance 15 and a high resistance 16, the inductance 15 being of such a value as to be resonant with the grid-cathode capacity for the frequency of the incoming currents from line 11, 11. In case the incoming currents 90 are of a plurality of frequencies, resonance should occur for that frequency or band of frequencies which is of the most importance. Resistance element 16 serves to broaden the tuning of the circuit including the grid capacity and inductance 15, thereby neutralizing the grid capacity over a wider range of frequencies than would occur in the case where only an inductance element was employed. The insertion of resistance 16 and 95 inductance 15 in the input circuit of repeater 5 has, therefore, been found to improve, to a considerable degree, the quality 100 of the transmission between lines 11 and 13.

The value of the resistance element 16 should 105 have depends, to a certain extent, upon the

value of the effective resistance and capacity between the input electrodes of the tube associated therewith. The higher the effective resistance between the grid and cathode, the smaller the value of resistance 16 in order to produce the desired effect. In one case, for example, it was found that resistance 16 should be of the order of half a megohm, in the case where the grid and cathode effective leakage resistance was approximately 3 megohms, and the effective capacity was 30 micro microfarads.

As an example of the value inductance 15 may have, it was found that with a vacuum tube having an effective capacity of 30 micro microfarads and effective leakage resistance of 3 megohms between its input electrodes for a frequency of 2000 cycles, inductance 15 should be approximately 200 20 henrys.

What is claimed is:

1. In combination, an amplifying device having an impedance comprising a resistance component and a reactance component, 25 an input circuit for said device, and means comprising a resistance and a reactance associated with said input circuit for substantially annulling said reactance component.

2. In combination, a vacuum tube, a translating device having an input circuit, the internal impedance of said tube with respect to the currents impressed on said input circuit comprising a resistance component and a capacity component, and a path comprising 35 an inductance and a resistance associated with said input circuit for substantially annulling said capacity component for the frequency of the impressed currents.

3. In combination, a vacuum tube having 40 an anode, a cathode and a control electrode, the impedance between said control electrode and said cathode comprising a resistance component and a capacity component, means for impressing current variations on said 45 control electrode and means for substantially annulling the capacity component between the two electrodes for the frequency of the currents impressed thereon, said means comprising an inductance and a resistance.

4. In combination, a vacuum tube having 50 an anode, a cathode and a control electrode, the impedance between said control electrode and said cathode comprising a resistance component and a capacity component, an incoming line, a transformer for impressing 55 on said control electrode current variations from said line, and means for substantially annulling said capacity component for the frequency of the currents impressed thereon,

said means comprising a resistance and an 60 inductance effectively in shunt to said line.

5. The combination of an incoming line, a vacuum tube amplifier for repeating without distortion, having an anode, a cathode and a control electrode, a transformer between said line and said amplifier, a path in shunt to said control electrode and said cathode with respect to said transformer, said path comprising a resistance and an inductance, the value of said inductance being dependent upon the internal characteristics of 70 said tube.

6. In combination, a vacuum tube having an anode, a cathode and a control electrode, the impedance between said control electrode 75 and said cathode comprising a resistance component and a capacity component, means for impressing current variations on said control electrode, a shunt path to said control electrode and said cathode comprising a resistance and an inductance, said inductance being of such a value as to resonate with said capacity for the frequency of said current variations, said resistance having a 80 value of the order of one half a megohm.

7. In combination, a vacuum tube having an anode, a cathode and a control electrode, the impedance between said control electrode and said cathode comprising a resistance component and a capacity component, 90 means for impressing current variations on said control electrode, and a path of inductive reactance and high resistance associated with said tube for substantially annulling said capacity component for the frequency 95 of the currents impressed on said tube.

8. In combination, an incoming line, an amplifying device associated therewith and having an impedance comprising a resistance component and reactance component, 100 and a path in shunt to said line of inductive reactance and high resistance for substantially annulling said reactance component.

9. In combination, an electron discharge device having an anode, a cathode, and a control electrode, a circuit comprising a transformer, means connecting said cathode and said control electrode across said circuit, and a path connected across said circuit and comprising a resistance and an inductance in series, the value of said inductance being dependent upon the internal characteristics of said tube.

In witness whereof, I hereunto subscribe my name this 1st day of November A. D., 115 1920.

JOSEPH B. MORRILL.
